UNITED STATES PATENT OFFICE.

AXEL G. GULBRANSEN, OF CHICAGO, ILLINOIS, ASSIGNOR TO GULBRANSEN-
DICKINSON CO., OF CHICAGO, ILLINOIS, A CORPORATION OF ILLINOIS.

VALVE MECHANISM FOR PLAYER-PIANO ACTIONS.

Application filed October 25, 1918. Serial No. 259,614.

To all whom it may concern:

Be it known that I, AXEL G. GULBRANSEN, a citizen of the United States, residing at Chicago, in the county of Cook and State 5 of Illinois, have invented a certain new and useful Improvement in Valve Mechanism for Player-Piano Actions, of which the following is a full, clear, concise, and exact description, reference being had to the accompanying drawings, forming a part of 10 this specification.

My invention relates generally to player pianos or instruments of like character and has special reference to pneumatic valve 15 mechanism for such instruments.

The successful operation of a player piano, as judged by the user, depends largely upon two important features, 20 namely, ease of operation and accuracy, uniformity and quickness of response of the pneumatic action to the corresponding note perforation of the music roll.

As a certain amount of power is required to sound each note, the aggregate amount 25 of power required to operate the instrument is readily seen to depend upon the number and length of notes struck. This is really very little, but the power which the operator must furnish at the pedals is in many instruments so great as to spoil the pleasure 30 of playing the instrument.

The amount of power applied at the 35 pedals in excess of that actually expended in the playing mechanism is lost either in leakage of air at the valves or other parts of the system, or in performing unnecessary work due to faulty design or operation.

As there are eighty eight notes in a standard instrument and as each note must have 40 its own valve and pneumatic it is at once evident that the design and operation of the valves and pneumatics is of the greatest importance in producing a good instrument. If the valves are leaky or take more power 45 than is necessary, the instrument plays hard. If the valves and pneumatics waste power due to poor design or any other cause, the same thing is true.

If on the other hand, the valves have insufficient power or do not respond instantly 50 the instrument operates feebly or slowly and will fail to make quick repetition.

I have found that the speed at which the valves must operate to give the desired 55 quickness of playing is so great that a rigid

valve tends to rebound and is noisy. I have conceived the idea of breaking the moving parts of the valve as a whole into a plurality of rigid parts connected by yielding flexible parts. Thereby I gain a double advantage. The impact of the valves is taken up quietly and instantly, preventing noise and avoiding leakage and in addition the flexible yielding connection serves as a universal joint of limited motion and causes the 60 valve to seat invariably and instantly. This latter feature overcomes leakage and permits the instrument to operate with surprising speed and uniformity, even in spite of the small inaccuracies in the manufacture 65 and assembly of the parts incidental to large scale production.

To insure accurate and responsive valve seating I mount the valve on its stem by means of a reduced flexible pad. 75

To increase the speed and power of the valve operating diaphragm, I have provided a disc working in connection with the usual diaphragm to permit the pressure of the air upon the diaphragm to be applied instantaneously and without developing detrimental local stresses in the diaphragm. I have connected this disc to the diaphragm by a yieldable and flexible connecting member which prevents any sidestrain or localized concentration of pressure upon the diaphragm. Long life of the diaphragm is thus assured. The disc in turn is connected to the valve stem by a yieldable and flexible connecting member so that there are yieldable and flexible members between the various elements of the valve and its operating mechanisms and the entire mechanism is light and 80 strong. I preferably employ small pads of a soft fibrous material such as felt to form 85 the flexible and yieldable connecting members. Other means, such for instance as a spring, may be employed. 90

I wish to call attention to the fact that the two features of flexibility and yieldability are separable and either one alone 95 may be used to advantage, although I find it convenient in the preferred form of my invention to secure both functions in one structure.

Other advantages and features of my invention will be apparent from a detailed description of the preferred embodiment of the invention.

My invention will be more readily under- 110

stood by reference to said drawings illustrating a preferred embodiment thereof, and in which:

Figure 1 is a fragmentary view, in elevation, of a piano player pneumatic action, shown partly in section to better illustrate the invention;

Figure 2 is an enlarged fragmentary sectional view of the valve and its co-operating parts; and

Figure 3 is a detail fragmentary horizontal section on the line 3-3 of Figure 2.

In said drawings 1 is a channel board similar to that used in many such piano actions, extending horizontally the length of the piano key board and supported at its ends upon suitable brackets or other supports. Upon the rear face of the channel is mounted a bank of pneumatics 2 arranged in three horizontal rows and in vertical staggered relation and connected by individual abstracts 3 to operating levers 4 which engage suitable parts of a piano action to produce playing.

25 The pneumatics 2 are of usual or any preferred construction, consisting of an upper fixed leaf 5 and a lower hinged leaf 6, the two leaves being connected by a collapsible fabric 7 to form a bellows. Each pneumatic
30 is secured to the under side of a block 8 which is glued or otherwise fastened to the rear face of the channel board 1 and which block 8 contains the valve mechanism for the pneumatic. The hinged board 6 of the bellows is hinged adjacent to the channel board and its opposite end is extended beyond the bellows for connection to the upper end of the corresponding abstract by a connection permitting a limited rocking motion.
35
40

The blocks 8 each contain a valve 9 which controls the action of the bellows. The valve 9 is controlled by the note perforations in the note sheet through the proper tracker bar opening to admit suction to or shut suction off from the corresponding pneumatic. The valve 9 comprises a flat disc head 10 and a grooved guide stem 11, the head operating within a chamber 12 to control atmospheric and suction ports entering same. A passageway 13 connects the chamber 12 with the interior of the pneumatic 2. Normally, the interior of the pneumatic is connected to the atmosphere through the port 14 formed in the pliable seat 15 which closes the top of the valve chamber 12. This pliable seat is formed of a plurality of discs or laminations of cardboard, fibre or the like. I preferably provide rounded edges 16 on the valve seat 15 at the ends of the port 14. The valve head 10 when in the normally inactive position seats on a valve seat 17 and thus controls communication between the valve chamber 12 and the exhaust passageway 13. The

exhaust passageway 18 extends into the channel board 1 and connects with a suction channel 19 extending horizontally from end to end of the channel board 1. The air is exhausted from this channel 19 by 70 exhaust devices, such as suitable bellows constituting part of the usual player piano mechanism. The suction in the passageway 18 is normally active at the port 10' under the valve head 10 to hold the latter upon 75 the seat 17 and is also active upon the upper surface of a diaphragm 20 arranged in a diaphragm chamber 21, below the valve, and which diaphragm partitions the diaphragm chamber and engages the lower end 80 of the grooved valve stem 11. The diaphragm is normally inactive by reason of suction being applied to the under side thereof. This suction is transmitted from the suction channel 19 through the bleeder 85 opening 22 and down through the passage 23 and 23', into the lower part of the diaphragm chamber 21. There are a plurality of these passages 23, one for each of the pneumatics 2 drilled down through the channel board 1 to different depths to effect communication with the diaphragm chambers of respective pneumatics. The upper ends 90 of these passages 23 connect with transverse horizontal passageways 26 drilled in the channel board, which have communication through nipple 27 with tubes 28 which lead to corresponding perforations in the tracker board.

It will be apparent that when the opening 100 in the tracker board is uncovered by perforations in a note sheet, atmospheric pressure will be transmitted through the tube 28 and into the passageway 23 faster than the same can be exhausted through the 105 bleeder valve 22. In consequence of this the atmospheric pressure acts upon the under side of the diaphragm and lifts the valve 9, opening the exhaust port 10' beneath the valve head 10 and closing the 110 atmospheric port 14 above the valve head 10. By lifting of the valve 10, the passage 13 which leads to the pneumatic is disconnected from the atmosphere and is connected to the suction passage 19; consequently the pneumatic 2 collapses and through its abstract 3, lever 4 and the proper mechanical connections it causes the piano string to be struck and the note sounded. 115

The several bleeder openings 22 are accessible through registering openings 29 in the channel board 1 and which openings are closed by a strip 30 secured by screws 31, a soft packing strip 32 being provided to render the joints tight. These bleeder openings are in small sheet metal button-like members which can be readily cleaned, renewed or changed for members having different sized ports or openings in order to obtain the desired rapidity of action. It is 136

obvious that when the tracker opening is again closed, the passage 23 with its connections and the lower part of the diaphragm chamber are exhausted through the 5 bleeder opening, and in consequence the diaphragm is rendered inactive. The valve 9 drops, opening the port 14 and closing the port 10', thus placing the interior of the pneumatic in communication with the 10 atmosphere and permitting same to open or expand.

Referring now particularly to the valve 9 and its co-operating devices,—I have provided a valve which will accurately and 15 tightly seat in both directions whether the two seats are absolutely parallel or not, and whether or not the contacting surfaces of the valve head and seats are accurately at right angles to the bore in which the valve 20 moves. For this purpose I connect the head to the valve stem 11 by means of a yielding joint member 33 which can be a small piece of felt, relatively soft leather, or other suitable yielding material. I connect the 25 head and the stem to the yielding connector 33 by glueing or otherwise permanently joining them. This provides a universal joint of limited motion. I build up the 30 valve head of a rigid middle disc 34, preferably wood, faced on the top and bottom with thin leather or some other similar relatively soft material 35. As mentioned hereinbefore, the seat 15 is yielding. I preferably build it up of a number of layers 35 of cardboard, leather, or some other suitable material. I preferably make the stem 11 smaller than the bore 36 in which it is contained, so that the stem will move freely therein. It might occur that if the head 40 and stem were rigidly connected, the stem would prevent the accurate seating of the valve. By means of my yielding connection, which is aptly described as a universal joint, between these parts, the head 10 is 45 free to be tightly seated upon the upper seat 14 or the lower seat 17 regardless of the relative alignment of the head and stem 11. The seat 17 is formed of a small metal thimble 37 which is flared or coned enough 50 to provide a tight fit when the same is forced or driven into place in the block 8. The thimble 37 is seated in the bore 36 with its upper end projecting slightly above the lower wall 38 of the valve chamber 12. 55 The leather surfaces on the valve head not only assist in the tight closing of the valve, but also in providing a quiet action of the valve.

The diaphragm which is preferably made 60 of thin leather is of large area relatively to the area of the valve stem, and for the purpose of enlarging the area of contact between these two parts I provide an enlargement non-rigidly associated with the 65 lower end of the stem 11, in the form of a

disk 39 of cardboard, wood or the like, generally termed a pressure distributing member. I connect to the lower end of the stem 11 in central relation thereto by means of a yielding pad or connector 40 similar to the connector 33 at the upper end of the valve. I preferably make the disk 39 of pasteboard, which is light and relatively rigid, and I prefer to make the disk considerably larger than the stem 11 and smaller than the diaphragm, so that the disk is arranged to bear upon the diaphragm about midway between the pad 40 and the edge of the diaphragm. 70

To further cushion the diaphragm on the valve I provide a flexible pad 41 centrally below the disk 39 and preferably, but not necessarily, secured thereto. I make this pad 41 thick enough to fill in between the curvature of the diaphragm when inactive and the disk 39 so that, as best illustrated 80 in Figure 2, the diaphragm, when inactive, normally touches the outer edge of the disk 39. Thus there are flexible or universal connections between all rigid parts of the valve 85 as a whole, and between the diaphragm and the rigid disk member 39. 90

The yielding pad 40 between the disk 39 and the valve 11 serves as a universal joint to permit the disk to accommodate itself to the diaphragm without producing any 95 undue or detrimental friction upon the valve; in other words, if the diaphragm should not rise uniformly the disk 39 can yield relatively to the valve to accommodate itself to such action, thus lessening any 100 tendency to cocking or tilting the valve. The disc with its pads forms a distributing member connected by a universal joint of limited motion between the diaphragm and the valve stem. 105

By means of the enlarged lower end of the stem which the disk provides, I secure a quicker and more positive lifting of the valve, when the diaphragm operates, due to the greater area over which pressure is applied to the valve. Also the disk 39 and the pressure pad 41 present a greater area of contact 110 between the valve and diaphragm which prevents undue or sharp flexing of the diaphragm. 115

I claim:

1. A valve for a player piano action, comprising a valve head and a stem and a pad of soft fibrous material glued to the head and to the end of the stem and forming the sole connection between these two parts, said pad having a cross-sectional area less than that of the stem. 120

2. In a valve mechanism of the kind described, a valve, a relatively thin flexible diaphragm for moving the valve, a substantially rigid disk carried by the valve for contact with the diaphragm, and a yielding pad interposed between the disk and the diaphragm, the diaphragm normally contacting 125

with the disk adjacent its periphery and with said pad, whereby the diaphragm is prevented from extreme flexing at any point.

3. In a valve mechanism of the kind described, a relatively thin flexible diaphragm, a valve having a stem arranged centrally relatively to the diaphragm, a substantially rigid disk on the stem for contact with the diaphragm, a yielding pad securing the disk centrally to the valve stem, and a yielding pad between the disk and the diaphragm.

4. In combination, a valve block having a recess in the top for forming a valve chamber, a valve seat member comprising a disc having its edges secured to the block about said recess, a passageway extending thru said member to atmosphere, an operating pneumatic having its stationary board secured to the lower face of the valve block, a passageway from the valve chamber to said pneumatic, a metallic ring seated in the lower wall of said chamber and forming a lower valve seat, a vertical passageway concentric with said ring, a diaphragm chamber formed in the stationary board of the pneumatic below said vertical passageway, a diaphragm for the diaphragm chamber, a main suction passageway intersecting and communicating with the vertical passageway at an intermediate point, a passageway leading from the chamber below the diaphragm to a tracker board opening, a flat disc valve mounted in the valve chamber, a stem of a diameter substantially the same size as the vertical passageway guided therein and a pad of soft fibrous material glued to the bottom of the valve disk and to the top of the stem to permit movement of the disk into different planes.

5. In combination, a valve block having a recess in the top for forming a valve chamber, a valve seat member comprising a disc having its edges secured to the block about said recess, a passageway extending thru said member to atmosphere, an operating pneumatic having its stationary board secured to the lower face of the valve block, a passageway from the valve chamber to said pneumatic, a metallic ring seated in the lower wall of said chamber and forming a lower valve seat, a vertical passageway concentric with said ring, a diaphragm chamber formed in the stationary board of the pneumatic below said vertical passageway, a diaphragm for the diaphragm chamber, a main suction passageway intersecting and communicating with the vertical passageway at an intermediate point, a passageway leading from the chamber below the diaphragm to a tracker board opening, a flat non-rigid disc valve mounted in the valve chamber, a stem of a diameter substantially the same size as the vertical passageway guided therein, a

disc resting upon the diaphragm, a pad of soft fibrous material glued to the bottom of the stem and to the top of the disc.

6. In a valve mechanism, a flexible diaphragm, a valve stem, a valve, a flexible compressible pad of a cross section less than that of said stem glued between said valve and the end of said stem and forming the sole connection therebetween, a flexible compressible pad at the other end of said stem, and a disc smaller than said flexible diaphragm and larger than the cross-section of said stem operatively disposed between said compressible pad and said diaphragm whereby the motion of said diaphragm is transmitted through said disc to said stem.

7. A valve comprising, in combination, a head, a stem, and a flexible pad between the two forming a universal connection, said stem being of greater radial dimensions than said pad throughout predetermined portions of its periphery and of less dimensions than said pad throughout the remaining portions.

8. In a valve mechanism of the kind described, a valve having a head and a guide stem, a flexible diaphragm for lifting the valve, means carried by the stem and resting on the diaphragm for increasing the effective area of contact between the stem and the diaphragm, and a pad of yieldable material interposed between said means and the stem to positively connect the same.

9. In combination, a block having a valve chamber and a flexible disk of laminated fibrous material secured over the valve chamber to form a valve seat, a valve having universal movement and adapted to engage said seat, said disc being perforated to provide a passageway.

10. In combination, a diaphragm, a valve stem, a pressure distributor, the distributor contacting with the diaphragm, a pad of soft fibrous material lying between the central portion of the distributor and the diaphragm, and a pad of soft fibrous material secured between the end of the valve stem and the adjacent face of the distributor and forming the sole connection therebetween.

11. A valve comprising, in combination, a head, a stem, and a flexible pad between the two forming a universal connection, said stem being of greater radial dimensions than said pad throughout predetermined symmetrically disposed portions of its periphery and of less dimensions than said pad throughout the remaining portions.

12. A valve for a player piano action, comprising a valve head, a stem, and a pad of soft fibrous material secured to the head and to the end of the stem and forming the sole connection between these two parts, said pad having radial dimensions less than those of the stem, but a cross sectional area greater than that of the stem.

13. A valve comprising, in combination, a head, a stem, and a resilient pad between the same, said pad making contact on one side over a circular area and on the other 5 side over a smaller cross-shaped area.

14. A valve comprising, in combination, a head, a stem, and a resilient pad between the same, said pad making contact on one side over a circular area and on the other 10 side over a smaller cross-shaped area having arms of the same radial dimensions as said circular area.

15. A valve comprising, in combination, a stem of cross-shaped cross section, a circular disk adjacent one end of said stem, and a resilient pad having contact on one side with said disk and on a portion of the other side with a portion of the end of said stem.

20 16. A valve comprising, in combination, a stem, an actuating diaphragm, and a contact disk of radial dimensions intermediate between those of the stem and diaphragm,

said disk being flexibly attached to said stem.

17. A valve comprising, in combination, a stem, a head, said stem and head having their opposed surfaces composed of different materials having different rigidity, and a flexible pad interposed between said surfaces, the contact surface between the pad and the material of greater rigidity being less than the contact surface between the pad and the material of less rigidity.

18. In a valve mechanism, in combination, a valve head, a valve stem, a flexible pad glued between said head and stem and constituting the sole connection between them, and means for actuating said stem, said pad connection being capable of carrying 40 tension to support the stem suspended from the head.

In witness whereof I hereunto subscribe my name this 22nd day of October, A. D. 1918.

AXEL G. GULBRANSEN.
